ATTORNEY.

UNITED STATES PATENT OFFICE.

SIDNEY O. BIGNEY, OF ATTLEBORO, MASSACHUSETTS.

DESIGN FOR A COIN-HOLDER AND VINAIGRETTE.

42,182.

Specification for Design.

Patented Feb. 20, 1912.

Application filed July 5, 1910. Serial No. 570,501. Term of patent 3½ years.

To all whom it may concern:

Be it known that I, SIDNEY O. BIGNEY, a citizen of the United States, residing at Attleboro, in the county of Bristol and State of Massachusetts, have invented a certain new, original, and ornamental Design for a Coin-Holder and Vinaigrette, of which the following is a specification.

In the accompanying drawings which form a part of this specification, the figure is a side elevation of a coin holder and vinaigrette embodying my new design.

I claim,

The ornamental design for a coin holder and vinaigrette, as shown.

SIDNEY O. BIGNEY.

Witnesses:

HARRY E. CARPENTER,
EDITH C. PIKE,
ETHEL W. WITHERELL.
